UNITED STATES PATENT OFFICE.

CARRODUS BASTOW, OF LYNDHURST, NEW JERSEY, ASSIGNOR TO THOMAS POTTER,
SONS & CO., INC., OF NEW YORK, N. Y., A CORPORATION OF PENNSYLVANIA.

DESIGN FOR AN ARTICLE OF MANUFACTURE.

48,850.

Specification for Design.

Patented Apr. 11, 1916.

Application filed October 21, 1915. Serial No. 57,201. Term of patent 3½ years.

To all whom it may concern:

Be it known that I, CARRODUS BASTOW, a subject of the King of Great Britain, and a resident of Lyndhurst, in the county of Bergen and State of New Jersey, have invented a new, original, and ornamental Design for an Article of Manufacture, of which the following is a specification, reference being had to the accompanying drawing, forming a part thereof.

The figure is a plan view of my design to be applied to an article of manufacture.

The design comprises a perspective view of the city of New York looking from the bay, and showing the Statue of Liberty in the foreground, the East River with three East River bridges being shown to the right, and many boats of different kinds being shown in the Hudson River to the left as

well as in the East River. At the corners of the perspective view there are floriated panels, and above and below the perspective view, there are chain borders. At one end there are views of the United States Sub-Treasury and of Grant's Tomb, which views are each inclosed in a floriated oval panel, the panels being disposed side by side and being inclosed within floriated rectangular borders, there being a similar floriated border at the other end of the design.

I claim:

The ornamental design for an article of manufacture as shown and described.

CARRODUS BASTOW.
